WITNESS

O. J. Hartman.

INVENTOR
Frederick R. Smith
BY Cyrus N. Anderson
ATTORNEY

UNITED STATES PATENT OFFICE.

FREDERICK R. SMITH, OF PLAINS, PENNSYLVANIA.

SLATE PICKER.

Application filed July 8, 1924. Serial No. 724,769.

My invention relates to slate picking means for effecting the removal of slate and other material, consisting of relatively flat particles, from coal in the washing and separation of coal from slate and other like impurities. The coal and the slate are subjected to the action of water and by reason of the fact that the specific gravity of the slate is greater than that of the coal the former is discharged from the coal washing apparatus at a lower point, while the latter, that is the coal, is discharged from a higher point of the apparatus. However, it not infrequently happens that some portion of slate remains in the coal which is discharged and it is desirable that such portion be removed. It is therefore a general object of the present invention to provide means whereby such slate as may have remained intermixed with the coal which is discharged from the washing apparatus shall be picked out and separated therefrom.

Another object of the invention is to provide a slate picking or removing means which is adapted for application to and to be embodied within the chute through which the coal is discharged from the jig pan of a coal jig structure such as that shown in the patent to Henry W. Falker No. 1,055,731 granted March 11, 1913.

Another object of the invention is to provide slate picking or separating means of the character indicated with means whereby the same may be readily adjusted to adapt it to the conditions which may be met in practice.

To these and other ends my invention comprehends the construction as hereinafter described in detail, particularly pointed out in the claim and as illustrated in the accompanying drawing in which I have illustrated one convenient form of embodiment of the same. It will be understood that my invention is susceptible of embodiment in other forms of construction than that shown and that various changes in the details thereof may be made within the scope of the claim without departing from the said invention.

50 In the drawing:

Fig. 1 is a top plan view of a chute embodying my invention which is adapted for receiving and discharging coal from a jig

pan, or other washing means, of a coal washing apparatus;

Fig. 2 is a view in side elevation looking at the lower side of Fig. 1; and

Fig. 3 is a view taken on the line 3—3 of Fig. 1.

Referring to the drawing: 1 and 2 designate the opposite sides of a chute having a bottom comprising plates 3 and 4 which are provided with perforations, as shown. The upper portion of the plate 4 is provided with an unperforated flange-like portion 5 by means of which it is connected to the forward end of a jig pan, not shown. The sides 1 and 2 are likewise provided with rear end portions 6 and 7 which are adapted for connection with the forward end portions of the sides of said jig pan.

In the present construction the intermediate portion of the bottom of the chute comprises flat bars 10 one end of each of which is provided with projecting cylindrical portions 11 which constitute trunnions. These portions extend through openings 12 in the side 1 of the chute and are journaled therein. The opposite ends of the flat plates or bars 10 are provided with outwardly projecting portions 15 which extend through openings 16 through a plate 17 secured upon the outer side of the side 2 of the chute by means of rivets 18. The plate 17 overlies and covers up an opening 20 formed by cutting away a portion of the lower edge of the side 2 as best shown in Fig. 3 of the drawing. The purpose of employing the plate or bar 17 is to facilitate the assembling of the parts which make up the structure. The projections 16 are provided with handle-like portions 21 which extend substantially at right angles thereto in parallel relation to the side 2 of the chute. The upper ends of these handle-like portions 21 extend through openings 22 in the horizontal flange 23 of an angle member the other vertical flange 24 of which is secured to the upper edge portion of the side 2 by means of bolts 25 which extend through the said side and through slots 26 which are provided in and extend longitudinally of the said flange 24.

The angle member is adapted to be clamped in any position to which it may be adjusted by means of nuts 27 upon the bolts 25. By adjusting the handle-like portions 21 the

plates or bars 10 may be adjusted to any plane desired. For instance, they may be positioned so as to lie in a common or single plane or they may be adjusted so as to provide relatively long and narrow openings between the edges thereof as indicated in Figs. 2 and 3 of the drawing. The upper edge of the uppermost or right-hand plate or bar 10 is separated from the lower edge 10 of the perforated plate 4, as indicated at 30. This opening as well as the openings between the adjacent edges of the several plates should be of widths to permit the passage therethrough of the particles of slate which are of flat formation but not of sufficient width to permit of the passage therethrough of the coal which is being discharged through the said chute.

The purpose of the present construction is 20 to provide means adapted for embodiment within and as a part of a chute structure whereby such slate as may not have been separated out of the coal during the jiggling and washing operation may be separated 25 therefrom during its discharge through the chute from the jig pan and before it is sent out into commerce for use.

It will be seen that by my invention I have 30 provided a simple structure which may be installed economically for the purpose of effecting a final and a substantially complete separation of slate and other impurities in the form of relatively flat particles from coal before it is put into the market for use.

Having thus described my invention, what I claim and desire to secure by Letters Patent is:

In slate picking means for separating slate from coal, the combination of a chute having oppositely disposed sides and a bottom, a portion of which bottom consists of bars arranged transversely thereof and in edge to edge relation with respect to each other, each of which bars is provided with projections at its opposite ends, one of the 45 sides of the said chute being provided with openings therethrough through which the 50 projections of the said bars at one side of the said chute bottom extend, a portion of the lower edge of the opposite side of the said chute being cut away, a plate secured to said side over the opening formed by cutting away the said lower edge portion, said plate having openings therethrough through 55 which the projections at the opposite ends of said bars extend, extensions projecting from the last named projections and extending in parallel relation to the adjacent side of the said chute and means having adjustable connection with the said side and with the said extensions whereby the latter may be adjusted to effect rotatable adjustment of the 60 said bars.

In testimony that I claim the foregoing as my invention I have hereunto signed my 65 name this 12th day of March, A. D. 1924.

FREDERICK R. SMITH.
